UNITED STATES PATENT OFFICE

138,104

DESIGN FOR AN ENGINE CYLINDER BLOCK

Lloyd M. Taylor, San Leandro, Calif.

Application June 23, 1942, Serial No. 107,317

Term of patent 14 years

(Cl. D77—1)

To all whom it may concern:

Be it known that I, Lloyd M. Taylor, a citizen of the United States and a resident of the city of San Leandro, county of Alameda, State of California, have invented a new, original, and ornamental Design for an Engine Cylinder Block, of which the following is a specification, reference being had to the accompanying drawing, forming a part thereof.

Fig. 1 is a side perspective view of an engine cylinder block showing my new design; and

Fig. 2 is a perspective view showing the side and end opposite that illustrated in Fig. 1.

I claim:

The ornamental design for an engine cylinder block, as shown.

LLOYD M. TAYLOR.
